UNITED STATES PATENT OFFICE.

ROBERT F. MIEHLE, JR., OF CHICAGO, ILLINOIS, ASSIGNOR TO THE BELL & HOWELL COMPANY, OF CHICAGO, ILLINOIS, A CORPORATION OF ILLINOIS.

REEL.

Application filed April 26, 1926. Serial No. 104,574.

My invention relates particularly to motion picture film reels although not limited to this use alone.

The main feature of the invention relates 5 to the provision of a reel adapted for reverse mounting upon certain types of spindles constructed for cooperation with certain types of reels to prevent reverse mounting of these reels on said spindles, thus making it unnecessary to replace or change said 10 spindles on machines where it is desired to use a reel which may be reversely mounted.

With this feature in view my invention 15 consists in certain features of novelty in the construction, combination, and arrangement of parts by which the said feature and certain other features hereinafter appearing are effected, all as fully described with reference to the accompanying drawing and more particularly pointed out in the claims.

In the said drawing—

Figure 1 is a partial front elevation of a spindle mount having mounted thereon a reel embodying my invention.

Figure 2 is a side elevation of the spindle mount with the reel, shown in central vertical section, mounted thereon.

Figure 3 is a partial perspective view of the spindle, hereinafter described.

Figure 4 is a partial side view of the reel showing the side thereof opposite that shown in Fig 1.

Like characters of reference indicate like parts in the several views.

In the said drawing 1 designates a support arm, and mounted for rotation in a hub of this arm is a spindle 2, the reel mount portion of which extends outwardly from one end of the hub. This extending portion 40 of the spindle is provided with a longitudinally varied reel mount surface comprising a round outer portion 3 and a square or polygonal inner portion 4 having its faces tangential to the round portion and accordingly extending laterally beyond the round portion and terminating in an outwardly facing shoulder 5.

The reel includes spaced side plates 6 and 7 secured in a usual manner to opposite ends of a central tubular member 8, and the side plates 6 and 7 are provided with central spindle apertures 9 forming a spindle opening. Both of the apertures 9 are square or polygonal corresponding with the inner portion 4 of the reel mount portion of the

spindle to fit over the same for driving and centering the reel in the mounting of the reel on the spindle, and the sides of the openings 9 are tangent to circles of the same diameter as the outer round portion 3 of the spindle so that they fit over the same for centering the reel thereon. In the mounting of the reel on the spindle the spindle aperture 9 of one of the side plates of the reel engages on the inner portion 4 of the spindle 60 while the spindle aperture 9 of the other side plate engages on the outer portion 3 of the spindle as shown in Figs. 1 and 2. By reason of the fact that both apertures 9 will fit over the inner portion 4 of the spindle, 65 the reel may be reversely mounted thereon. The apertures 9 of the side plates 6 and 7 of the reel are preferably angularly offset, as shown in Fig. 4, so that there are provided in the spindle opening of the reel intermediate shoulders facing longitudinally of the spindle opening in opposite directions. These shoulders are adapted to engage against the shoulder 5 of the spindle in respective positions of the reel on the spindle to limit inward movement of the reel on the spindle. 70

A spring latch device 10 is carried by the spindle for engagement with one of the side plates 6 and 7, depending on the position of the reel on the spindle, to limit outward movement of the reel on the spindle, and is releasable to permit mounting of the reel on and removal of the reel from the spindle. 80

While I have herein shown and particularly described the preferred embodiment of my invention I do not wish to be limited to the precise details of construction shown as changes may readily be made without departing from the spirit of my invention, but having thus described my invention I claim 90 as new and desire to secure by Letters Patent the following:

1. A motion picture film reel or the like provided with a spindle opening comprising non-circular portions angularly offset whereby to form intermediate shoulders facing longitudinally of said opening in opposite directions, each of said portions being adapted to engage on an inner non-circular portion of a spindle for centering the reel and to engage on an outer portion of the spindle, beyond which said inner portion of the spindle extends laterally, for centering the reel. 100

2. A motion picture film reel or the like 110

- provided with a spindle aperture comprising polygonal portions angularly offset and forming intermediate shoulders facing longitudinally of said opening in opposite directions, the sides of said portions being tangent to circles of the same diameter. 3. A motion picture film reel or the like including two axially spaced side plates provided with non-circular spindle apertures angularly offset, each of said apertures being adapted to engage on an inner non-circular portion of a spindle for driving and centering the reel and to engage on an outer portion of the spindle, beyond which said inner portion of the spindle extends laterally, for centering the reel. 4. A motion picture film reel or the like including two axially spaced side plates provided with identical polygonal spindle apertures angularly offset and forming intermediate shoulders facing longitudinally of the spindle opening, formed by said aperture, in opposite directions. 5. A motion picture film reel or the like provided with a spindle opening comprising non-circular portions each adapted to engage on an inner non-circular portion of a spindle for driving and centering the reel and to engage on an outer portion of the spindle, beyond which said inner portion of the spindle extends laterally, for centering the reel. and to engage on an outer portion of the spindle, beyond which said inner portion of the spindle extends laterally, for centering the reel. 6. A motion picture film reel or the like provided with a non-circular spindle opening adapted to engage on an inner similar non-circular portion of a spindle for driving and centering the reel and to engage on an outer round portion of the spindle, beyond which said inner portion of the spindle extends laterally for centering the reel. 7. A motion picture film reel or the like including two axially spaced side plates provided with polygonal spindle apertures, the sides of said apertures being tangent to circles of the same diameter and each aperture being adapted to engage on an inner polygonal portion of a spindle for driving and centering the reel and to engage on an outer round portion of the spindle, with respect to which round portion the sides of the polygonal portion of the spindle are tangential for centering the reel.

In witness whereof I hereunto affix my signature this twenty-third day of April, 1926.

ROBERT F. MIEHLE, JR.
